A new patent application, Serial No. 263,166, is filed by Julius Rubin, Bronx, N. Y., for a "Thread Trimming Machine." The application is directed to a machine for removing threads from a garment after a sewing operation. The machine is designed to be mounted on a work table and to have a standard which may be secured to the machine housing. The machine is provided with a cutter assembly which is mounted on a bracket and which is supported by a motor platform. The cutter assembly is provided with a side opening and a pivoted plate for variably adjusting the effective size of said opening so as to correspondingly vary the vacuum existing in the housing. The front end of the housing is provided with a laterally adjustable toothed guide plate having bolts operating through slots and serving to secure the guide plate to the housing. The cutter assembly is mounted on a bracket which fits into the housing and renders the same substantially air tight where required. Integral with the bracket is a motor platform which supports the motor. The bracket and the platform may be a metal casting such as aluminum or the like. The portion of the bracket which is enclosed by the housing may take the form of an elongated right angle member comprising a floor and a lateral wall as illustrated in Figures 5 and 7. The floor is formed with an opening which communicates with the interior of the hollow standard so as to apply the vacuum to the housing. Formed rearwardly of the opening is a well which serves to accumulate oil applied through fitting for oiling the motive power transmission as will hereinafter be explained. Well may be emptied at any desired time. It will be observed that the front wall of well is arcuate and defines the rearward curvature of the opening. The purpose thereof is to intercept flying cut threads and direct them downwardly through the opening and standard. Wall thus functions as a barrier for threads trimmed by the cutter assembly and impelled rearwardly through the housing. Bracket further comprises a rear end wall which is embraced by the open end of the housing.

UNITED STATES PATENT OFFICE

2,661,519

THREAD TRIMMING MACHINE

Julius Rubin, Bronx, N. Y.

Application December 26, 1951, Serial No. 263,169

6 Claims.

(Cl. 26—11)

This invention relates to cutters for threads or the like such as may be found on dresses or other clothing after a sewing operation and which threads must be removed or trimmed from the clothing.

This application is directed to a cutting machine such as was described in my Patent No. 2,584,620, which was issued February 5, 1952, save that the instant application is concerned with only one of the cutting functions, i. e., thread trimming, rather than the two described in the prior application.

The instant invention discloses a thread cutting machine which trims hanging threads or the like from a sewn garment, the machine being of pronounced simplicity and economy relative to any prior devices of which I am aware. The machine is not only sturdy and compact but it permits adjustment of the cutter opening while employing the relatively heavy motor as a hand-held member and a stabilizing element and while further insuring the maintenance of a suction in the housing thereof notwithstanding variations in adjustment. Means are further provided to facilitate assembly and disassembly of the housing as well as the adjustment of the cutter opening in two perpendicularly related directions, these being accomplished by novel, effective and simple means. In addition, a simplified and effective means of adjusting the degree of vacuum employed to suck cut threads from the garments into a depository therefor is provided as is means for directing such cut threads into the depository.

The machine which will be hereinafter described and which incorporates the improvements above mentioned, not only performs its duties as well or better than prior devices, but reduces the cost thereof to a considerable and gratifying degree.

The invention will further be understood from the following description and drawings in which—

Figure 1 is a perspective view illustrating the complete apparatus and the power equipment therefor;

Figure 2 is an enlarged elevational side view of the cutting apparatus;

Figure 3 is a top plan view thereof;

Figure 4 is an enlarged cross-sectional view as taken along the line 4—4 of Figure 3;

Figure 5 is an enlarged cross-sectional view as taken along the line 5—5 of Figure 4;

Figure 6 is a plan view of the cutting head or cutting blade assembly and the toothed guide plate;

The invention is of a thread trimming apparatus which will be capable of stability and durability and which will be simple in construction and operation. The apparatus will be provided with a cutter assembly which is mounted on a bracket and which is supported by a motor platform. The cutter assembly is provided with a side opening and a pivoted plate for variably adjusting the effective size of said opening so as to correspondingly vary the vacuum existing in the housing. The front end of the housing is provided with a laterally adjustable toothed guide plate having bolts operating through slots and serving to secure the guide plate to the housing. The cutter assembly is mounted on a bracket which fits into the housing and renders the same substantially air tight where required. Integral with the bracket is a motor platform which supports the motor. The bracket and the platform may be a metal casting such as aluminum or the like. The portion of the bracket which is enclosed by the housing may take the form of an elongated right angle member comprising a floor and a lateral wall as illustrated in Figures 5 and 7. The floor is formed with an opening which communicates with the interior of the hollow standard so as to apply the vacuum to the housing. Formed rearwardly of the opening is a well which serves to accumulate oil applied through fitting for oiling the motive power transmission as will hereinafter be explained. Well may be emptied at any desired time. It will be observed that the front wall of well is arcuate and defines the rearward curvature of the opening. The purpose thereof is to intercept flying cut threads and direct them downwardly through the opening and standard. Wall thus functions as a barrier for threads trimmed by the cutter assembly and impelled rearwardly through the housing.

Bracket further comprises a rear end wall which is embraced by the open end of the housing.

The invention is of a thread trimming apparatus which will be capable of stability and durability and which will be simple in construction and operation.

The invention is of a thread trimming apparatus which will be capable of stability and durability and which will be simple in construction and operation.

The invention is of a thread trimming apparatus which will be capable of stability and durability and which will be simple in construction and operation.

Figure 7 is a cross-sectional view as taken along the line 7—7 of Figure 4; and

Figure 8 is a cross-sectional view as taken along the line 8—8 of Figure 5.

5 When in use, the machine is mounted on a standard 20 which may be secured to a work table 21. The standard 20 may be integral with or secured to the machine housing 22 and is hollow so as to be adapted for the application of a vacuum therethrough for sucking cut threads into the vacuum apparatus or depository 23 through the hose 24. The vacuum apparatus 23 is conventional and may assume any desired form.

10 In the form shown, the housing 22 is rectangular and supports the thread cutting apparatus. It is formed with a side opening 25 and a pivoted plate 26 for variably adjusting the effective size of said opening so as to correspondingly vary the vacuum existing in housing 22. The front end of the housing is provided with a laterally adjustable toothed guide plate 27 having bolts 28 operating through slots 29 and serving to secure the guide plate 27 to the housing 22. As will hereinafter be made clear, lateral adjustment of plate 27 effects a correspondingly lateral adjustment of the cutter opening.

15 The cutter assembly is mounted on a bracket 30 which fits into the housing 22 and renders the same substantially air tight where required. Integral with the bracket 30 is a motor platform 31 which supports the motor 32 as by bolts 33. Thus, the bracket 30 and the platform 31 may be a metal casting such as aluminum or the like.

The portion of bracket 30 which is enclosed by the housing 22 may take the form of an elongated right angle member comprising a floor 31a and a lateral wall 32a as illustrated in Figures 5 and 7. Floor 31a is formed with an opening 33 which communicates with the interior of hollow standard 20 so as to apply the vacuum to the housing. Formed rearwardly of opening 33 is a well 34 which serves to accumulate oil applied through fitting 35 for oiling the motive power transmission as will hereinafter be explained. Well 34

40 may be emptied at any desired time. It will be observed that front wall 36 of well 34 is arcuate and defines the rearward curvature of opening 33. The purpose thereof is to intercept flying cut threads and direct them downwardly through opening 33 and standard 20. Wall 36 thus functions as a barrier for threads trimmed by the cutter assembly and impelled rearwardly through the housing 22.

45 Bracket 30 further comprises a rear end wall 40 which is embraced by the open end of housing 22.

so as to enclose the same. Wall 40 is formed with a peripheral slot 41 in which is disposed a live rubber gasket 42. It will be noted that gasket 42 is of greater width than the depth of slot 41 so that when wall 40 is inserted in a housing 22, the gasket 5 holds over to enhance its sealing function by being pinched between wall 40 and housing 22.

End wall 40 is formed with a central opening 45 through which extends sleeve 46 which is connected as by screw 47 to shaft 48 of the 10 motor 32. Thus sleeve 46 rotates pursuant to the operation of motor 32. A screw 49, operating through sleeve 46, secures pin 49a eccentrically on the front end face of sleeve 48. Thus, rotation of sleeve 48 causes eccentric pin 49a to revolve as will be evident. Pin 49a is disposed between parallel stationary pins 50 which are connected to pivoted lever arm 51. Lever arm 51 comprises the operating arm of the cutter assembly and it is pivoted to the wall 32a of bracket 20 30 at the pivot pin 52. A washer 53 provides clearance between wall 32a and lever arm 51 and a collar 54, secured to pin 52 maintains the lever arm 51 secured and rotatably mounted on pin 52.

Lever arm 51 is formed with a dog 60 at its 25 front end which is received in a slot of movable cutter blade 61. The cutter assembly includes leaf spring 62 for holding movable cutter blade 61 in position, and a stationary cutter blade 63. Movable cutter blade 61 is slidably maintained 30 against the stationary cutter blade 63 by the leaf spring 62 so that these parts are handled as a unit. A folded supporting member 64 is mounted on the front end 65 of the bracket 30 and a bolt 66, extending through plate 67, secures the cutter head to the front end of bracket 30.

Essentially the cutter operates by reciprocation, through dog 60, of the movable toothed cutter blade 61 which cuts threads against the stationary toothed cutter blade 63. Toothed plate 40 27 is connected across the front open end of housing 22 adjacent to the stationary cutter blade 63 and serves as a guide for the thread cutter as well as to determine the width of the cutter opening between the plate 27 and the cutter head 45 or assembly per se.

Assembly of the apparatus is effected by inserting the bracket 30 into the rear open end of housing 22 until the rear wall 40 encloses such open end. The gasket 42 serves as an air seal 50 at this point. Such insertion will also bring the cutter assembly into position at the front open end of housing 22 and where its cutter teeth are properly adjacent the teeth of guide plate 27. Bracket 30 is secured to the floor of housing 22 55 by bolts 75 operating in slots 76. By this means, the bracket 30 is capable of longitudinal adjustment relative to the housing 22. The purpose thereof is to afford a longitudinal adjustment between the cutter head and the toothed guide plate 27. In this manner the cutter opening may be varied longitudinally as well as laterally as above described. The purpose in permitting such a variation is to permit adjustment of the cutter opening in accordance with individual preferences and the type of threads being cut. Thus, very fine threads or very fine fabrics on which the threads are used may require a similar cutter opening.

It will be recognized that the longitudinal adjustment of the bracket 30 within housing 22 is best effected by grasping the motor 32 in the hands and then shifting the bracket and motor bodily until the cutter head is in the proper position whereupon the bolts 75 may be tightened in 70 75

their slots 76. The heavy motor thus serves as a stabilizing element in accomplishing proper positioning of the bracket and of the cutter assembly mounted thereon. The thickness of rear or end wall 40 is considerable as illustrated so that the required adjustment of the bracket 30 in housing 22 may be made without destroying the effective air tight nature of housing 22. Thus, the thickness of wall 40 should be as great or greater than the length of slots 76.

The height of the machine may be adjusted by loosening the set screws 77 on the collar 78 which embraces the standard 20.

The operation of the instant apparatus will be evident from the above description. Briefly, the angular bracket 30 having been suitably longitudinally adjusted and the bolts 75 tightened when the proper longitudinal extent of the cutter opening has been set, the plate 27 may then be laterally adjusted to achieve the desired lateral width of the cutter opening. Such adjustment may depend on the type of garment material or threads; or the individual preference of the operator. The vacuum apparatus 23 is then put into operation in order to produce a vacuum in the housing 22. Pivoted plate 26 may be adjusted for the desired degree of vacuum or suction. Electric motor 32 is then energized so as to rotate sleeve 46. Such rotation causes eccentric pin 49a to revolve between pins 50 and produces pivoting of lever arm 51 and consequent oscillation of dog 60. This oscillates the movable cutter blade so as to accomplish the cutting action.

The operator then takes a sewn garment or the like and holds the cut threads adjacent the cutter assembly. The vacuum draws the threads inwardly away from the garment per se and the cutter blades shear and trim such threads. The cut threads are pulled inwardly by the vacuum through opening 33, standard 20, hose 24 into the vacuum apparatus or depository 23. Thus, the garment is trimmed with safety and efficiency through the simplified form of apparatus described herein.

What is claimed is:

1. A thread cutting machine comprising a housing, a bracket supported within said housing, a toothed guide plate connected at one end of said housing and a thread cutter, blade assembly connected at an adjacent end of said bracket so that said thread cutter blade assembly is disposed adjacent to said guide plate, and a motor for operating said thread cutter being mounted on the other end of said bracket, said bracket being longitudinally adjustable relative to said housing so as to correspondingly adjust said blade assembly relative to said guide plate.

2. A thread cutting machine comprising a housing, a bracket fitting into and enclosed by said housing, a toothed guide plate connected at one end of said housing and a thread cutter blade assembly connected at an adjacent end of said bracket so that said thread cutter blade assembly is disposed adjacent to said guide plate for forming a cutter opening therebetween, said bracket being longitudinally adjustable relative to said housing so as to produce a corresponding longitudinal adjustment between said blade assembly and said guide plate, said guide plate being normally laterally spaced from said blade assembly and being further laterally adjustable relative thereto, and a motor for operating said blade assembly mounted on said bracket and externally of said housing, said motor being adapted to be grasped by the hand so as to afford lon-

itudinal adjustment of said blade assembly relative to said tooth guide plate whereby said cutter opening may be adjusted from two perpendicularly related directions.

3. A thread cutting machine comprising a rectangular open ended housing, a bracket maintained within said housing, a toothed guide plate mounted on the front open end of said housing and partially enclosing said front end, a cutter blade assembly mounted on the front end of said bracket so as to be normally adjacent said guide plate and forming a cutter opening therebetween, said toothed guide plate being laterally adjustable on said housing front end so as to correspondingly vary said cutter opening, said bracket being longitudinally adjustable relative to said housing so as to correspondingly longitudinally vary said cutter opening, and a motor for operating said cutter blade assembly mounted on the rear end of said bracket and externally of said housing, said motor being adapted to be grasped by the hand for facilitating longitudinal adjustment of said bracket relative to said housing, and means to tighten said bracket relative to said housing.

4. A machine according to claim 3 and wherein said housing is formed with an opening in a wall thereof, said housing being formed with a second opening in another wall thereof, means for applying a vacuum through said second opening so as to produce a vacuum through said housing, and a slidable plate adjacent to said first-named opening for variably covering said first-named opening to adjust the degree of vacuum through said housing.

5. A thread cutting machine comprising a housing, a cutter blade assembly disposed at one end of said housing for cutting threads applied thereto, said housing having an opening in a wall thereof adapted to have a suction applied therethrough so as to produce a vacuum in said housing for drawing cut threads therethrough, motor means including a rotatable sleeve and motive

transmission means within said housing for operating said cutter blade assembly, a fitting on a wall of said housing and adapted to have lubricating oil applied therethrough for lubricating said motive transmission means, and a well disposed below said motive transmission means and said fitting for receiving excess oil, said well having a front wall adjacent to and defining the rear wall of said suction opening whereby sucked in cut threads are guided by said well front wall into said opening.

6. A thread cutting machine comprising an elongated housing having front and rear open ends, an elongated L-shaped bracket maintained within said housing, a thread cutter blade assembly mounted at one end of said bracket and disposed in the front open end of said housing, said bracket being longitudinally adjustable relative to said housing so as to vary the longitudinal position of said thread cutter blade assembly relative to said housing front open end, and a rear wall formed on said bracket and embraced by the rear open end of said housing, said rear wall having a peripheral slot formed therein, and a gasket disposed in said slot, said gasket being wider than said slot and being bent over so as to be embraced between the periphery of said rear wall and said housing, the thickness of said rear wall being greater than the extent of adjustment permitted between said housing and said bracket.

JULIUS RUBIN.
